UNITED STATES PATENT OFFICE.

GEORGE SCOTT CHILES, OF CHICAGO, ILLINOIS.

RAILWAY-TRUCK CONSTRUCTION.

Application filed May 17, 1921. Serial No. 470,465.

To all whom it may concern:

Be it known that I, GEORGE SCOTT CHILES, a citizen of the United States, resident of Chicago, county of Cook, and State of Illinois, have invented a new and useful Improvement in Railway-Truck Constructions, of which the following is a specification.

My invention relates to railway car truck frames and the details involved in the form of the frames, springs and bolsters and has for its object, first the formation of the metal in the side frame whereby the greatest economy of metal is made possible with the lowest average maximum fibre stresses, measured in terms of the total weight of the structure, and second to a convenient form of the shape of the parts for assembly and repair, together with the forms that are cheaply constructed.

The general features of my invention permit a somewhat variable degree as relates to the details of the shapes of some of the parts and I have shown several different forms of the details, all of which fall within the general features and general object of the invention.

The invention is set forth in the claims.

Reference will be had to the accompanying drawings in which Figure 1 is a side sectional elevation of a truck side frame embodying my invention, the wheels and axles of the truck being indicated only in dotted lines.

Figure 2 is a sectional view on line 2—2 of Figure 1. Figure 3 is a plan section on line 3—3 of Figure 1. Figure 4 is an elevational detail of an end of the bolster shown in Figures 1, 2 and 3. Figure 5 is a sectional elevation of the spring cap block shown in Figures 1 to 5 inclusive. Figure 6 is the preferred form as relates to the details involved that differentiate it from the other figures and shows substantially the same end elevation as that involved in Figure 1, in so far as any different features are involved. Figure 7 is a plan section of

the parts shown in Figure 6 and Figure 8 is a sectional elevation on line 8—8 of Figure 6.

Figure 9 is another modified form of the details of the spring, bolster and side frame connections and Figure 10 is a plan section of the parts shown in Figure 9. Figure 11 is a vertical section elevation on line 11—11 of Figure 9. Figure 12 is another modified form of the details of the bolster, spring and side frame details and Figure 13 is a plan sectional view of the parts shown in Figure 12 on line 13—13 of Figure 12. Figure 14 is an end elevation of the side frame, bolster and spring details, modified from the form shown in the other views.

Figure 15 is a front elevation, 16 is a plan section and 17 is a vertical section of a modified form of seating the springs in the side frame. However, the method of seating these springs as shown in the previous figures is preferred to the method indicated by Figures 15, 16 and 17. Figure 18 is a detail of a filler block used for adjusting the heights of the springs. Figure 19 is a diagrammatical form of the strain lines attendant with the ordinary methods employed in the forms of side frames for trucks heretofore generally used. Figure 20 is a diagrammatical view of the strain lines involved in the use of my side frame as shown by this invention. Figure 21 shows old side frame with my strain line marked thereon.

In the drawing 1 indicates the wheels in dotted lines, of the ordinary car truck and 2 indicates the axle positions. 3 indicates the direct vertical pressure lines of the car truck bearings on the axle. 4, as a general expression, indicates the side frame regardless of the details involved in the several detail figures.

I prefer to make my side frames out of cast steel or other suitable metal, but forged or fabricated side frames may be substituted instead, in so far as they conform to the specific useful and novel features of my invention.

- 5 indicates the body of the bolster inside and beyond the limits of the variation in the details of the bolster in connection to the side frame and the springs, and this 5 part of the bolster may be of any suitable form or construction, adapted to be used with the details which relates entirely to the ends of the bolster as shown in this invention.
- 10 Heretofore, it has been the common practice with a truck construction somewhat analogous to this, to employ what is known as a spring plank or a connection across from the side frame to side frame in the 15 lower region and upon this plank the springs have been mounted, but with my construction I may or may not use this spring plank, suiting the preference of the user of the trucks. But I show a spring plank in some 20 of the forms and this is indicated by 6 in Figures 9 and 11.
- In the preferred form as indicated by Figures 6, 7 and 8 the bolster 5 is provided with T shaped ends indicated by 7 which 25 are provided with the inside flanges 8 and the outward projecting flanges 9 and to these latter flanges there are riveted, by the rivets 13, small angle blocks 10 which perform the same function as the flanges 8.
- 30 In this form the side frame is provided with straight columns 11 which guide the bolster in place through the medium of the bearing surfaces 12 on the T ends of the bolsters. These columns are embraced by the 35 flanges 8 and angle blocks 10 against lateral displacement of the bolster.
- The truck is assembled when the flanges 10 are absent and the rivets 13 are put in after the bolster is in place and on taking 40 the assembly of the truck down the rivets 13 are cut out and on reassembly the rivets are replaced.
- The lower girder or tension member of the side frame is indicated by 14 and is 45 here shown curved in a peculiar way as indicated by 15 as will be described more particularly in relation to the diagrammatic views showing the strain lines. This tension girder 14 of the side frame is provided 50 with some offset spring seats as indicated by 16 and are cast integral as the web member of the tension member and on the inner surfaces of these spring seats there are little projections indicated by 17 which center 55 and locate the springs in their proper places.
- The springs are indicated by 18 and are seated in the T end 7 of the bolster by corresponding projections to those of 17, but here indicated by 19. These projections are cast 60 in the body of the metal and involve no expense beyond the weight of the material required in their construction.
- The structure shown in Figures 9, 10 and 65 11 differs from that shown in Figures 6 to 8 inclusive, only in the detail arrangement of the columns of the side frame and the flanges on the T head of the bolster ends. In Figures 9 to 11 inclusive the columns are provided with clearance spaces or offsets on bearing surfaces which guide the bolster as 70 is indicated by 20. This widened space between the columns at the 20 locations is called the bolster opening and when the springs and spring plank are removed, the bolster may be dropped down into this opening and the end flanges of the T heads of the bolster be withdrawn from the bolster openings and by this means the truck is assembled in the way that is commonly well known.
- The T ends of the bolster in the form shown by Figures 9 and 11 differ only in that there is an integral flange 21 on the front end of the bolster which takes the place of the angle flange 10 shown as riveted on in Figure 7.
- The spring plank 6 is shown in Figures 9 to 11 as being connected simply by means of the projections 17 for the two middle springs only.
- The form shown by Figures 12 and 13 differs from that shown by Figures 9 and 11 inclusive by having the bolster opening at the top of the columns 11 instead of the lower region of the columns and this opening in Figures 12 and 13 is indicated by 22 in Figure 12, and further instead of having the T ends integral with the bolster body I make the end or spring cap block a separate piece 23, which has the corresponding flanges 8 and 21 which embrace the column guides in the same manner as in the previously described figures as relates to these parts.
- The bolster ends used with these blocks 23, 105 is indicated by Figure 4 and is provided with some flanges or shoulders 24 which lock down over the sides of the block 23 as indicated by the dotted lines in Figure 13 and thus the bolster is secured to this block 23 110 amounting in the result to substantially form the T head of the bolster ends as indicated by Figure 6 and Figure 9.
- In assembling and taking down the truck frame of the form shown by Figures 12 and 13 the bolster itself is first lifted up, freeing the flanges 24 from the embrace of the block 23 and then the side frames are withdrawn laterally and then the blocks 23 may be lifted into the bolster opening 22 and removed as desired.
- The form shown in Figure 14 differs from that shown in Figures 12 and 13 in that the bolster opening is at the lower ends of the columns and instead of the flanges 8 and 21 on the block 26 over the springs, I provide some flanges 25 cast integral with the side frame itself and these flanges serve to take the end thrust of the block which rides on the springs, which block in Figure 14 is in- 125 130

dicated by 26, and this block is substantially like the block 23, save only the guide flanges 8 and 21 are wanting and the side flanges 25 serve the same purpose by embracing the ends of the block 26.

The structures shown in Figures 1 to 3 inclusive have the bolster opening at the top, as is the case in Figure 12 and this opening is here indicated also by the numerals 22. The ends of the bolster as shown in Figures 1 to 3 inclusive is of the same form as is shown in Figures 12 to 14 inclusive, but in Figures 1 to 3 inclusive the block which rides on the springs is shown by Figure 5 and is indicated by 27 and this block differs but slightly from the blocks 23 and 26. However, the guideways for taking the end thrusts of the bolster as transmitted through the block 27 are cast integral on to the side frame as is indicated by the flanges 28 and this feature as relates to taking the end thrusts is substantially the same as that indicated by figure 25 in Figure 14, so far as the end thrusts alone are concerned.

However, it is desirable when convenient, to have the bearing surfaces of the guideways for the bolster in the side frame to come up as high as is permissible in connection with the other features of the structure so that these bearing surfaces may come directly in line or on the same level with the center plate of the bolster which is indicated by 29 in Figure 1. Thus the arrangement of the lateral guide ways as indicated by the structures shown by Figures 6, 9 and 14 come nearly to the desired position as relates to the center bearing of the truck.

In the truck various holes are shown as core vents which are involved only in the matter of casting the parts to an economical advantage and some of them may act as water drains as well as is indicated by the hole 30 in Figure 5. In Figures 15, 16 and 17 I have shown a modified construction for holding the springs 18 in place and I do this by projections 31 (see Figure 16), located on the outer margins of the springs and these take the place of the projections 17 and 19 as previously described in the other figures.

Some small plates 32 shown in Figures 15 to 18 inclusive, serve as shims for adjusting the tension of the springs as may be desired and for the purpose of adjusting the center line of the couplers of the car to fit the standard specification for such heights. These plates 32 may be employed in the other structures where they are not shown in the drawing.

The location of my springs 18 as I have shown them are in tandem line lengthwise of the side frame and furnish a wide face of support for holding the bolster in direct upright position with more security than has generally been obtained by nesting the

springs in rectangular form as heretofore has been the general practice.

Heavy shocks such as running over crossings, bad rail joints, the application of the brakes and sometimes by reason of the wheels being engaged by bumping blocks, induce severe rocking motion transmitted to the bolster by the thrust or impact of the car, which frequently breaks the king pin and unseats the center plate of the bolster from the car body bolster, but with my construction those strains are more easily sustained with less tilt or movement of the bolster than has heretofore been obtained by the old style construction of rectangular nested springs.

By reason of the T ends of my bolster or what amounts to the same thing, the cross blocks to which the bolster is connected to the ends, furnishes a stronger connection to resist lateral twisting side frame movements that serve to hold the side frames in relative position to each other through the medium of the bolster itself in so much better form that the spring plank is less needed with my structure than with the structures formerly generally used.

There is often encountered in the railway service trucks which have been pushed as it were, diamond shaped, from some accidental cause which ordinarily is termed "truck bound" as relates to the wheels which cause the wheels to bind heavily on the flanges on the rails or actually produce derailments from such diamond deformation of the truck forms. My structure is less liable to such accidental displacements than the form of truck generally used.

A great advantage in truck construction is obtained by my invention in the economical use of the metal in taking the strains as is shown by the diagrammatical view of my design as compared with the diagrammatical view Figures 19 and 21 of the old designs generally used.

It is a feature of mechanics and strength of material which is almost axiomatic, namely, that in a piece of metal that is to bear strains, that the metal be so shaped and proportioned that the most members that are strained shall have as much as possible uniform stresses per square inch, so that no one part may be so much stronger than the immediate one adjacent to it that the weaker section will be caused to stretch more than the larger section, for then fracture is induced at this zone, which is forced to bear a greater initial per square inch load than its neighbor.

The idea I wish to convey may be well understood when I say that in breaking a bar of steel it is easily done by simply making a little crack or crease or fracture as desired, and then applying sudden shock thereto and by reason of the extra stretch

that is involved on those local fibres of the narrowed section the bar is readily cracked off. Thus the design of the tension member of my frame shown in the diagrammatical view Figure 20, the strain lines 33 having the spring application points 34 are so located that the metal throughout the tension zone is as nearly uniformly strained so that there is little or no local over stress in any one point and I obtain this by reason of the curved line 33 as described, which answers to the natural strain line described by a flexible cord loaded the same as the frame is loaded by the application of the load points 34 which correspond to the points at which the load is applied, through the medium of the spring locations as I have shown.

The form of my side frame amounts to the suspension bridge system of loading and the same as an inverted arch, the difference being chiefly that in the bridge construction the weight of the bridge itself is the principal load, whereas, in a side frame the side frame weight is an immaterial matter. However, in the bridge forms the service load moves, but the load is substantially static in so far as its location on the truck frame members is concerned.

An examination of Figure 19 will show that the strain line 35 as commonly attendant with the generally used old form of the side frame involves a compound system of strain features not only involved in the suspension idea but also direct beam and tension features 36, which cannot well be aligned up to arrive at the uniform unit stresses on the metal that I arrive at by the strain line form which I use as shown by Figure 20, which is really a natural suspension method and by this means I am able to use less metal and have a general lower average of unit stresses on the metal than has heretofore been arrived at, which is a great desideratum.

My strain line transferred to the old frame is indicated by 37 on Figure 21 and passes outside of the normal sections of the metal which shows the ambiguity of strains in the various parts of the old forms.

By making my side frame an integral casting I am permitted as it were, to use some parts of the metal to a double purpose and make a total lighter weight construction having the corresponding relative strength, than is possible with a built up structure. For illustration, see Figures 8—9—12—14—15, wherein the web of the channel section tension member forms not only the seats for the springs but also acts as the actual web of the channel itself and thus these parts support the load carried by the springs and at the same time are in tension with the load sustaining catenary curve tension member of the side frame. Not only are these spring seats used to take tension load

but they also contribute in sustaining the end thrusts of the bolster as they are a part of the girder or beam feature of the side frame when placed in transverse strain. In a built up structure no such economical use as just described can be made of the metal. Further, in securing the parts together of a built up structure rivet holes and other cavities necessarily employed to hold the parts together result in making useless as a tension feature not only the immediate section where the apertures take place, but substantially results in making useless the entire length of the member for that amount of metal represented by the aperture. With my spring seats integral as described and a part of the tension member seated down between the flanges of the tension member provide through the medium of the side flanges of the tension member, side walls or holding flanges of the springs without the employment of additional metal, which additional metal would not be used in tension were it in a built up structure. However, as I have shown it the side flanges of the tension member form this additional side guard feature to hold the springs in place without any additional expense of metal not used in tension.

What I claim is:—

1. In a structure of the class described, a side frame construction having the tension member on substantially a suspension line curve and with seats for the springs located along the said tension line, said seats for the springs being formed integrally of the web of a tension member forming part of the said web. 95

2. In a structure of the class described, the tension member of the side frame arranged substantially in a suspension line curve and with the springs located tandem along at several steps on this suspension line tension member, the said steps forming seats for the said springs and made integral 100 with the tension member and forming a part of the web section of the tension member. 105

3. In a structure of the class described, the side frame having a strut member at the top and a tension member on the lower region and the latter member substantially in the form of a suspension line curve and with the springs located tandem along the said suspension line curve; in combination with a bolster having ends wider than the main body of the bolster and adapted to ride on the said tandem arrangement of the springs. 110

4. In a structure of the class described, a side frame having the compression member and the tension member cast together in a unit casting and the tension member substantially in the form of a suspension line curve and with seats for the springs arranged tandem along the said tension line upon the said ten- 120 125 130 135 140 145 150

sion member, the said seats for the said springs being a part of the web structure of the tension member.

5. In a structure of the class described, a side frame composed of an integral casting having a compression member and a tension member and the latter in substantially a suspension line curve and provided with seats for springs arranged on the tension member in tandem alinement along the member; in combination with a bolster having bearing blocks at the ends of the bolster adapted to cover and bear upon the said tandem alined springs.

15. 6. In a structure of the class described, a side frame cast as a unit piece having a compression member and a tension member and the said tension member arranged on a suspension line curve and provided with seats 20 for springs arranged in tandem alinement along the length of the tension member; in combination with a bolster having integrally connected T ends adapted to ride upon the tandem arranged springs, and flanged guideways arranged between the side frame and the bolster to hold the bolster in transverse position from side frame to side frame.

7. In a device of the class described, a side frame having a suspension alined curved 25 tension member and spring seats alined tandem along the said member, a spring plank connecting the two side frames together transversely and located in the central region of the tension member; in combination with a bolster provided with end 35 members adapted to ride on the tandem arranged springs on the said tension members, and the said spring seats forming a part of the tension member and the web structure 40 thereof.

8. In a structure of the class described, a side frame having a tension member in the form of a suspension alined curve, and provided with seats for springs on the tension member located in tandem arrangement 45 along the said member; in combination with a bolster provided with cross members at the ends adapted to ride on the tandem arranged springs.

50. 9. In a structure of the class described, a side frame having seats for springs located in a tandem line across and within the bolster opening, and said opening being wider than normally required for the width of the 55 bolster itself; in combination with a bolster having widened end blocks adapted to seat upon the tandem arranged springs.

10. In a structure of the class described, side frames provided with seats on the tension member for a series of coiled springs located in tandem arrangement along the tension member and between the columns, with blocks riding on the said springs and adapted to support a bolster on the said 65 blocks, and means for registering blocks and

bolster in position together and means for guiding the said blocks in vertical sliding arrangement and against lateral displacement in the side frames.

11. In a structure of the class described, a tension member provided with tandem arranged spring seats adapted to support the bolster on springs located in the said seats and a bolster mounted across from side frame to side frame and provided with bearing seats 70 adapted to ride on the said tandem arranged springs and said bolster and side frame provided with vertically arranged guideways 75 adapted to hold the bolster in position in the side frame and riveted on flanges on the bolster for holding the bolster in position in the side frame after the parts are assembled.

12. In a structure of the class described, side frames having bolster openings materially wider than the bolster itself and provided with vertical guideways in the sides of the bolster openings, and having a suspension alined curved tension member with the springs arranged thereon in tandem alinement between the columns; in combination with a bolster connected to cross blocks on the ends and said cross blocks mounted in the guideways of the side frames and adapted to furnish a support for holding the side frames in parallel relation to each other.

13. In a car truck, side frames formed of integral castings and provided with bolster openings materially wider than the width of the bolster and with vertically arranged guideways on the sides of the bolster openings adapted to coact with bearing parts connected to the bolster for holding the two side frames in parallel relationship with each other, a series of tandem arranged springs mounted across and within the bolster opening and adapted to carry the load upon the tension member of the side frame; in combination with a bolster extending across from side frame to side frame and having spring bearing seats across the ends 100 of the bolster and with registering surfaces on the ends of the spring bearing seat members adapted to register in the vertical guideways of the bolster opening.

14. In a structure of the class described, a side frame provided with seats for a series of coiled springs located in tandem arrangement along the length of the side frame; in combination with a bolster extending from side frame to side frame and riding upon 110 tandem arranged springs, with a series of adjusting washers seated under the individual springs in a manner that the adjustment and tension of the springs may be made by the addition or removal of the said washers 115 for the purpose of sustaining the bolster in level arrangement and also for adjusting the height of the support of the car body for registration of the draw bars in proper standard height from the rail.

15. In a structure of the class described, a side frame construction having a tension member on substantially a suspension aligned curve and with seats for the springs located along the said tension line and the said tension member having a web section and side flanges, and said seats for the springs located on the web member of the said tension member and said flanges extending upward from the said seats for the springs and the said

seats for the springs located across and within the bolster opening.

Signed at Chicago, in the county of Cook and State of Illinois, this 10 day of May, 1921.

GEORGE SCOTT CHILES.
